UNITED STATES PATENT OFFICE.

WILLIAM J. MITCHELL, OF PRINCETON, KENTUCKY.

PLANTER AND FERTILIZER-DISTRIBUTER.

SPECIFICATION forming part of Letters Patent No. 423,794, dated March 18, 1890.

Application filed October 4, 1889. Serial No. 326,053. (No model.)

To all whom it may concern:

Be it known that I, WILLIAM J. MITCHELL, a citizen of the United States of America, residing at Princeton, in the county of Caldwell 5 and State of Kentucky, have invented certain new and useful Improvements in Planters and Fertilizers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to combined seed-planters and fertilizer-distributors; and it consists in the improved construction hereinafter described and set forth, whereby a simple and efficient arrangement is provided 20 that will positively and automatically effect the dropping of the grain and fertilizer in even hills and at working distances.

The invention further consists in certain details of construction and features herein- 25 after described and set forth.

In the accompanying drawings, Figure 1 is a plan view of a machine embodying my improvements. Fig. 2 is a transverse section taken in the plane of the hoppers and drill- 30 tubes, Fig. 1, the view being taken through the plane of the seed-hoppers and operating devices. Fig. 3 is a longitudinal sectional view through the central projecting lever, and connections for adjusting the position of 35 the main frame. Fig. 4 is a detail plan view of the lever and cam for engaging and disengaging the seed-actuating levers with the main draft-wheels. Figs. 5 and 6 are detail views. Fig. 7 is a detail longitudinal section 40 through one of the drill-tubes and adjacent parts.

The main frame of my machine consists of two longitudinal side bars A A, which are connected together at their ends by front and rear 45 transverse bars B B, intermediately braced by central longitudinal bars C C. Adjacent to and parallel with the front bar B is a transverse bar D.

The main carrying-axle 1 of the machine is 50 journaled in the side bars A A by means of suitable straps a, and has rigidly keyed on

the projecting ends thereof the two carrying-wheels E E. The main carrying-axle aforesaid is grooved within the main frame and adjacent to each side to receive two straps 55 b b, which are connected to short depending bars c c, joined together at their lower ends by means of a rear transverse bar d, reduced at its respective ends to form the bearing of the stub-axles for small wheels e e. A central vertical lever F has secured to its upper edge a strap f, which is curved to embrace a grooved portion in the main axle and has its lower end connected to the rear lower transverse bar d, while its upper end extends 60 through a slot formed in the central longitudinal beam G, located between the bars C C, and the said lever further extends through a slotted inclined seat-support H, the upper end of which carries a seat I. On each side 7c of the seat-support is located a lateral ear h, which carries a vertical pivot-pin upon which is mounted a lever i, one end of which carries a lug j, extending through one of the sides of the seat-support and projects into 75 the slot thereof, while the other end has connected therewith a leaf-spring k, the free end of which bears against the adjacent side of the seat-support and normally holds one end of the said member away from the side of the 80 seat-support, while the other end is thrown to a position that insures its lug being always located within the slot of said support.

By reference to the plan view, Fig. 1, it will be observed that the lugs of the respective members are oppositely located, and that the shape of said lugs is such that when said lever contacts with them through its throw in either direction it will strike a curved face and force said lug back against the tension 85 exerted by the spring, and after passing said lug the latter will be again projected into the slot of the seat-support and lock said lever at the limit of its throw in either direction.

On each side bar A A and abutting against 95 the transverse bar D is located a seed-hopper J, which is provided at its top with a hinged metallic cover l, while said hopper is internally divided by a transverse partition m into a front and rear compartment. Vertically - depending end boards depend from the under side of each hopper, as shown in-

Fig. 7, a metallic strap *n*, secured to the under side of the hopper and to the adjacent bars, and beams embracing the inner and outer sides and bottom of said boards to form 5 in connection therewith a recess or chamber having a lateral perforation formed in the sides thereof for the passage of the seed-slide. On the outer side of each seed-hopper, and likewise the depending chamber, is secured a 10 vertical tube *M*, which at its lower end intersects the heel *o* of a runner *N*, the vertical portions 23 of which are respectively bolted to the transverse bar *D* and front bar *B*. The heel of said runner has a vertical slot in 15 alignment with the delivery-tube. The seed-slide plays through the lateral openings in the side of the block and is provided with two vertical perforations to receive the charge from the respective chambers of the hopper, 20 so as to carry the same beyond the limits of the block, and when within the grain-drill to insure their dropping vertically through the same and through the recesses in the runner beneath. By reference to Fig. 7 it will be 25 noted that the seed and fertilizer slide is of shape in cross-section, and the lateral opening in the block and adjacent grain-tube being the same, its positive reciprocation will be insured at all times.

30 P P refer, respectively, to the levers for reciprocating the grain-slides upon the movement of the main carrying-wheels, and each of said levers consists of a main longitudinal portion 4, which is centrally pivoted upon 35 one of the side beams *A* of the main frame, and has its rear free end curved vertically, while the opposite portion has a loop 5 formed therein to embrace a supplemental block 6, attached to the inner side of the adjacent side bar, and the balance of said lever 40 consists in a downwardly-extending terminal portion 7, entering the inner slotted end of the seed-slide below and permanently retained in said slot by means of a securing- 45 pin. On the inner side of the supplemental block 6, near its rear part, is secured one end of a spring-plate 8, the curved free end of which bears against the loop formed in the slide-operating lever, so as to normally throw 50 its rear curved end in the direction of the inner side face of the adjacent main carrying-wheel. This latter is provided on its inner side and near its periphery with metallic cam projections or ears *g*, which are 55 shown in Fig. 1, consisting each of an abrupt face and an inclined one. As will be seen, the projections for each wheel are only two in number and are oppositely located.

From the partial description herein furnished it will be apparent that as the machine moves over the ground in a forward direction the rear curved ends of the slide-operating levers will contact with the inclined faces of the projections on the carrying-wheels and 65 result in the movement of the slides in one direction. Of course as the limit of said inclined face is reached the leaf-spring bearing

against the loop portion of each lever will tend to throw the curved rear ends again in the direction of the inner faces of the carrying-wheels, and thereby result in the movement of the seed-slide in an opposite direction, both of which movements occasion a reciprocation of the seed-slides. By having the two distinct portions for each slide and individual openings for the front and rear chambers of each hopper both seed and fertilizer may be taken therefrom in measured quantities and delivered through the drill-tube and recessed runner beneath. The drop operation only occurs twice in one revolution of each carrying-wheel, and inasmuch as the rear face of each projection is an abrupt one, as previously referred to, any reverse rotation of either wheel will result in a locking 80 of the slide-lever and its slide and prevent the delivery of an excessive quantity of the grain or fertilizer. I have found it convenient to provide the periphery of each carrying-wheel with two oppositely-located enlargements 10, each located a slight distance in the rear of the point occupied by the preceding projection, so that as the respective carrying-wheels travel over the ground they will relatively indicate the neighborhood in 85 which each charge is deposited.

A vertical shaft *Q* is journaled in one of the central beams *C*, and has its upper end bent to form an operating-crank, while its lower end projects beneath the bottom of said beam and has rigidly attached thereto a plate *R*, extending at one side to form an ear for the pivotal connection of a transverse horizontal rod *o'*, which is supported by and plays through a loop located on the other side of the companion bar *C*, the free end of said rod *o'* being flattened and normally located in proximity to one of the loop portions of the adjacent slide-operating lever. The plate *R*, at the other side of its connection with the vertical shaft, is curved to form a cam-edge *q*, which terminates in the shoulder *r*, said cam-edge and shoulder being at all times very closely positioned relative to the loop of the other slide-operating lever. 110 When the machine is in operation, the plate and its connections occupy the position represented by full lines in Fig. 4; but when it is desired to disengage the slide-operating levers from actuation with respect to the main carrying-wheels it is only necessary to operate the shaft *Q*, through the medium of its crank-rod, so that the plate *R* will be returned to the position represented by dotted lines, thus projecting its rod *o'*, so that its 115 flattened end will bear against and move the loop portion of the adjacent slide-operating lever to vibrate the latter upon its pivot and throw the rear curved end away from contact with the projections on its carrying-wheel, while the opposite cam-face of the plate *R*, through the movement of said plate, forces the opposite loop of the other slide-lever and finally locks it and all parts con- 120 125 130 135

nected therewith and with the plate by having said loop bear against the shoulder *r*. It will be understood that the corresponding movement of the loop of the other lever also results in throwing the rear curved end of said lever out of position. By this means the planting operation is entirely suspended and controlled by the operator.

As will be readily understood, the supplemental wheel-frame presented by the bars *c* and small carrying-wheels *e* enables the attendant to readily depress or elevate said frame, which in the event of the former adjustment will effect the elevation of the rear part of the rear carrying-frame and its wheels, and thereby hold the marking-wheels out of position to adjust them relative to the ground, after which they may be lowered. To move said lever of the supplemental carrying-frame it will be necessary to vibrate one of the side members, so that said lever will be released from the lock of the same, after which the lever can be moved to the other extremity of the slot, and there automatically locked by the lug of the other member, as aforesaid.

The central slotted beam *G* projects at its front end a slight distance beyond the front bar *B* of the frame, and said projecting portion is transversely pierced by a horizontal pivot, upon the ends of which are pivotally mounted two foot-levers *11* *11*, the rear end of each of which is bent horizontally outward to form a pedal *12* at the base of the seat-supporting bar. Two metallic bars *13* *13* are rigidly secured to the sides of the tongue *14* at the rear thereof, and have extending portions embracing the sides of the projecting portion of the central bar, and are angularly recessed to engage corresponding angular portions of the foot-levers *11* *11*, so that as the tongue is vibrated it will cause a corresponding movement of said foot-levers, but in an opposite direction. By depressing said foot-levers the tongue will be thrown to a horizontal position. To limit the movement of the tongue and of the foot-levers the plates *13* *13* of the tongue have each a vertical elongated slot *15*, through which passes a bolt also bearing in the projecting portion of the central bar. The rear end of both side bars *A* *A* carries a metallic strap *16*, in which bears a rear transverse shaft *17*, the respective ends of which are enlarged for the attachment of a curved metallic plate *18*, which serves as a scraper for the periphery of the adjacent wheel. A lever *19*, secured on said shaft, extends adjacent to the driver's seat for its convenient operation.

The forward end of each side bar *A* projects for a slight distance beyond the front bar *B* for the bearing of a transverse horizontally-extending bar *20*, which is recessed to engage said projecting portion, a bolt *21* piercing the inner end of said bar and rigidly engaging the main frame. At the outer end each bar *20* is a freely depending arm *22*,

which serves as a marker at that side of the machine.

I claim—

1. The combination, in a planter and fertilizer-distributer, of a supporting-frame mounted upon carrying-wheels and provided at each side with a hopper containing front and rear chambers, a tube depending from each hopper and having irregularly-shaped lateral openings, of a correspondingly-shaped seed-slide playing through the same and having two pockets for the respective chambers in said hopper, and longitudinal slide-operating levers, each made in one piece, pivoted on the main frame and bent to directly engage the irregular seed-slides at a point beneath the main frame, and contacts on the main carrying-wheels, substantially as shown. 70 80 85

2. The combination, in a planter, of a main frame and its carrying-wheels, seed-hopper, and tube leading therefrom, together with the slide playing laterally through the tube below the main frame, a lever having a longitudinal portion pivoted on the main frame and curved on its rear end to be actuated by one of the carrying-wheels, intermediately looped and depending portion engaging said slide, and a leaf-spring secured to the main frame and bearing against said loop to maintain said lever in operative relation with the carrying-wheel, substantially as set forth. 90 95

3. The combination, in a planter, of the main frame provided with carrying-wheels 100 having inner projections, a hopper, depending drill and slide playing laterally through said drill below the main frame, and operating-levers having longitudinal portion pivoted upon said frame and engaging the projections on the carrying-wheel, intermediate looped portion, and depending end to engage the slide, a leaf-spring bearing against said loop, a vertical lever, and transverse bar *o* laterally shifted by the same to bear against 105 said loop to throw said lever out of position, substantially as set forth. 110

4. The combination, in a planter, of a main frame, its carrying-wheels having projections, seed-hoppers, drills and their slides, operating-levers actuated and arranged as set forth, springs bearing against said operating-levers, vertical shaft having a plate *R* at its base, and rod *o* connected at one side of said plate and adapted to be removed to bear 115 against one of the slide-operating levers, said plate *R* having a cam-edge and shoulder at its opposite side to bear against and lock the other slide-lever, substantially as described. 120

5. The combination, in a planter, of the 125 main frame and its carrying-wheels mounted upon the main axle, a supplemental frame provided with small wheels hung thereon, a pivoted lever operating said supplemental frame, an inclined slotted seat-bar through 130 which said lever extends, pivoted members located at each side thereof and provided with oppositely-located lugs extending in said slot to lock the lever at the limit of its throw

in either direction, and springs under the free ends of said members, substantially as set forth.

6. The combination of the main frame and 5 its carrying-wheels, the inclined seat-bar and seat, the tongue carrying the extended plates notched as described, and foot-levers having corresponding notched portions to engage said plates and pivoted as specified, having pedal

portions located at the base of said seat-bar, to substantially as set forth.

In testimony whereof I affix my signature in presence of two witnesses.

WILLIAM J. MITCHELL.
